UNITED STATES PATENT OFFICE.

RALPH P. WILTON, OF WRIGHTSVILLE, PENNSYLVANIA.

DESIGN FOR A RECEPTACLE FOR DISPENSING DRINKING-STRAWS.

43,730.

Specification for Design.

Patented Mar. 18, 1913.

Application filed January 9, 1913. Serial No. 741,098. Term of patent 14 years.

To all whom it may concern:

Be it known that I, RALPH P. WILTON, a citizen of the United States, residing at Wrightsville, in the county of York and State of Pennsylvania, have invented a new, original, and ornamental Design for Receptacles for Dispensing Drinking-Straws, of which the following is a specification, reference being had to the accompanying drawing, forming part thereof.

Figure 1 is a view in side elevation, showing my new design. Fig. 2 is a view in top plan.

I claim:

The ornamental design for a receptacle for dispensing drinking straws, as shown.

RALPH P. WILTON.

Witnesses:

W. B. CRUMBLING,

A. V. CUSHMAN.
